CLAIM

I claim the ornamental design for a breathable waterproof hat, as shown and described.

DESCRIPTION

FIG. 1 is a top front isometric view of a breathable waterproof hat in accordance with my new design;

FIG. 2 is a bottom front isometric view of the design of FIG. 1;

FIG. 3 is a front elevation view of the design of FIG. 1;

FIG. 4 is a rear elevation view of the design of FIG. 1;

FIG. 5 is a right side elevation view of the design of FIG. 1;

FIG. 6 is a top plan view of the design of FIG. 1; and,

FIG. 7 is a bottom plan view of the design of FIG. 1.

A left side elevation view of the design of FIG. 1 has been omitted, as it is a mirror image of the right side elevation view of FIG. 5.
